ATTORNEYS

UNITED STATES PATENT OFFICE.

ARTHUR G. HALL, OF SPARTA, WISCONSIN.

WALL PROTECTOR.

1,412,241.

Specification of Letters Patent. Patented Apr. 11, 1922.

Application filed May 9, 1921. Serial No. 468,190.

To all whom it may concern:

Be it known that I, ARTHUR G. HALL, a citizen of the United States, and a resident of Sparta, in the county of Monroe and 5 State of Wisconsin, have invented a new and useful Improvement in Wall Protectors, of which the following is a full, clear, and exact description.

My invention relates to attachments for 10 articles of furniture, and it consists in the combinations, constructions and arrangements herein described and claimed.

An object of my invention is to provide 15 an attachment for a bedstead, or like article of furniture, that is adapted to prevent the contact of the bedstead, or like article, with an adjacent wall.

A further object of my invention is to provide a device of the character described that 20 has a bumper or stop member made of a suitable material, such as rubber, and arranged to contact a wall in advance of an article to which the device is applied, whereby such article is prevented from contacting 25 the wall and injury to the wall or to the article thus obviated.

A further object of my invention is to provide a device of the character described 30 that can be quickly and easily adjusted to a bedstead or the like without the use of any tools and without any change in the usual construction of an ordinary bedstead being required.

A further object of my invention is to 35 provide a device of the character described that is simple in construction and operation, thoroughly effective for the purpose intended, and practical commercially.

Other objects and advantages will appear 40 in the following specification, and the novel features of the invention will be particularly pointed out in the appended claim.

My invention is illustrated in the accompanying drawings, forming part of this application, in which—

Figure 1 is a view showing the use and application of the device,

Figure 2 is an enlarged elevation of a 50 portion of the mechanism shown in Fig. 1, and

Figure 3 is a section along the line 3—3 of Fig. 2.

Referring now to the drawings, 1 denotes a bedstead that is ordinary in construction 55 and is provided with cylindrical legs or supports 2. The latter may be tubular or solid

and may have a section other than that of a cylinder.

Attached to certain of the legs 2, preferably adjacent to the floor 3, are similar stems 60

4, each provided with a bumper 5 at its outer or free end. The bumper 5 is made of rubber or any other suitable material that is not likely to injure a surface contacted and has shock absorbing qualities. In the pres- 65

ent instance, the bumper 5 is a knob-like member provided with a socket 6 in which is disposed a plug 7 formed with a threaded opening 8 in its end wall. A clamping member 9 has an integral rod-like shank 10 70

threaded at its end for engagement with the threaded opening 8. In the present instance, the clamping member 9 is substantially semi-cylindrical to conform with the contour of the leg 2 although obviously it 75

may be of other conformation. A cooperating clamping member 11 is likewise adapted to conform with the curvature of the leg 2 and has an integral extension 12 to one end thereof adapted to enter the adjacent end 80

of the tubular stem 4 and to contact both the shank 10 and the wall of the stem 4. The clamping members 9 and 11 are provided with cooperating similar lugs or extensions 13 and 14, respectively, through 85

which a bolt 15 is projected to connect the clamping members 9 and 11 and to clamp the same to opposite sides of the leg 2 so that the stem 4 will be held against move- 90

ment relative to the leg 2. A ring or ferrule 95

16 is slipped along the stem 4 to fit snugly against the clamping members. The plug 7 is screwed on the threaded end of the rod 10 until the bumper 5 abuts the end of the stem 4.

From the foregoing description of the various parts of the device, the operation thereof may be readily understood. Each leg 2 that is likely to be moved in contact with a wall, such as indicated at 17, is 100

equipped with the device which is secured thereto in adjusted position in the manner described. I preferably secure the device to the leg 2 adjacent to the floor so that the bumper 5 will contact the baseboard 18 105

of the wall if the bedstead is moved toward the latter as the portion of the wall above the baseboard is relatively more frangible or likely to be marred. The stem 4 is of suf- 110

cient length to prevent the contact of any portion of the bedstead with the wall when the bumper has been moved against the lat-

ter. Since the bumper is made of a relatively soft material, the wall is not likely to be injured or marred by the contact of the bumper therewith.

5 While I have shown the device applied to a bedstead, it is obvious that it may be applied to other articles of furniture having members similar to the legs or supports of the bedstead and that many modifications 10 and adaptations of the form of the device illustrated may be made without departing from the spirit and scope of my invention as disclosed in the foregoing and outlined more particularly in the appended claim.

I claim:

A device of the character described comprising cooperating clamping members adapted for engagement with a support, one of said clamping members being provided with an extension adapted to be positioned at right angles to the support, a tubular stem arranged to encompass the extension and to abut the clamping members at one end, and means engaging with the extension at its free end for supporting a bumper in position to abut the outer end of the tubular stem. 20 25

ARTHUR G. HALL.
